UNITED STATES PATENT OFFICE.

ANTHONY A. VORNDIEKE, OF CINCINNATI, OHIO, ASSIGNOR OF ONE-HALF TO THOMAS H. O'BRIEN, OF CINCINNATI, OHIO.

ELECTRIC STARTING, STOPPING, AND DETECTING DEVICE.

Application filed October 2, 1922. Serial No. 591,794.

To all whom it may concern:

Be it known that I, ANTHONY A. VORNDIEKE, a citizen of the United States, residing at the city of Cincinnati, in the county 5 of Hamilton and State of Ohio, have invented certain new and useful Improvements in Electric Starting, Stopping, and Detecting Devices, of which the following is a specification.

10 The object of my invention is to provide a cheap, simple and efficient device for starting and stopping, that is making and breaking a circuit for starting and stopping motors, fans, lighting systems, and the like, 15 and it may be applied to wireless radio systems and the like.

In carrying out my invention I provide a system of keys suitably mounted and connected with means and mechanism and operating in connection therewith, so that the 20 pressing of certain of these keys will move the parts, to form an electric circuit and operate any motor, dynamo, fan, electric system for lighting, wireless and radio apparatus. In the present instance one of the 25 keys must be operated three times, another one time and a third one twice; these operations will form the circuit; many other keys are provided and any combination may 30 be used to form the circuit, by operating any set of these keys, for example, one key may be operated four times and another twice and still another one time to form this circuit and setting the device in operation. 35 No one but the operator who is familiar with the combination of keys can make the circuit and thus set the device in operation.

Another object and feature of the invention 40 consists in the employment of means for breaking the circuit by an outsider, who, if he touch any of the keys and press same, will break the circuit and stop the further operation of the device, but in this way he 45 will form a new circuit which will give an alarm, flash a light or give some other kind of notice that the machine has been or is being tampered with by an outsider or some one not knowing the combination.

50 In order that the regular operator may stop the device and break the circuit, one key is provided, which he knows about, which may be manipulated by him, which will break the circuit and not set in the

alarm as it will not form the auxiliary circuit for so doing. 55

If any outsider or one not knowing the combination operate and manipulate any of the keys outside of the one just referred to (which will not form the alarm or auxiliary 60 circuit), the regular circuit will be broken and the notice or alarm will follow immediately; this alarm or notice may be at a near or at a distant point.

The keys and their supporting stems operate in connection with a series of plates extending across the bottom of the device and same plates are capable of being pushed downwardly to operate mechanism under the same and at their rear to operate in connection with revolving discs and knife switches and wires which lead to an electric current supply, to form the circuit and break same accordingly as the keys are operated in connection with said plates. 65 70 75

The device is one of great utility and its various features and advantages will readily become apparent from the following specification and claims, to which reference is hereby made. 80

Fig. 1, is a plan view, partly broken away to show construction,

Fig. 2, is a front view of the device,

Fig. 3, is a section on line 3—3 of Fig. 7,

Fig. 4, is a section on line 4—4 of Fig. 7, 85

Fig. 5, is a section on line 5—5 of Fig. 7,

Fig. 6, is a section on line 6—6 of Fig. 7,

Fig. 7, is a sectional plan taken on line 7—7 of Fig. 2,

Fig. 8, is a plan view of a plate used in 90 connection with the means for forming a circuit,

Fig. 9, is a plan view of the other plate used in connection with the plate referred to in Fig. 8, and 95

Fig. 10, is a part section taken on line 10—10 of Fig. 5.

In the drawings I show a box frame, formed of top 1, bottom 2, and the sides 3 and 4. I use two key bars 5 and 6 and 100 they may be of any form and supported in the box in any way.

I employ a multiplicity of keys as 8, 9, 10, 11, 12, 13, 14, 15, 16 and 17. I may use any number of keys and arrange them in 105 any way. These keys have stems as 18, which stems all pass through the guide bars 5 and 6 and coiled springs as 19 encircle

the said stems and extend from bar 5 to bar 6, a spring as 20 being employed in connection with the key 8, which does not encircle the stem used with said key, but is independent thereof.

At the bottom I employ two cross plates as 21 and 22. The plate 21 has backwardly extending arms 23 and 24 which are pivotally or loosely mounted on axle 25, the arm 10 23 has a further extension 26, which engages under a spring 27, this spring 27 is for the purpose of returning the plate 21 to a normal position. The lower plate 22 is under plate 21; this lower plate 22 is mounted 15 on a pair of arms 28, 28¹, see Fig. 5, which arms are pivotally mounted on an axle 29, and have upwardly extending fingers 30.

On the shaft 25 I mount a peculiarly shaped lever 31, this lever at the forward 20 end, at point 32 connects and operates in connection with the key 10. At its rear end it is mounted in a fibre connecting piece 33, which in turn carries the knife switch contact 34, a pin 35 which is mounted in lever 25 31 engages into a recess 36 of finger 30 on the arms 28; a pin 37 engages onto the spring 38, said spring being for the purpose of returning lever 31 to its normal position; this spring 38 also has a forward extension 39, which engages onto the nose 40 of the 30 arms 28, which is also for the purpose of returning said arms 28 to their normal position.

In the bracket 41, on the pin 42 I pivotally mount a lever 43. This lever 43 works in connection with key stem 18 at the point 44, and at this point I fasten one end of the spring 20, the upper end of which being fastened to the guide bar 5.

40 At the rear end of the lever 43 on the pin 45, I pivotally mount a lever pawl 46, at the lower end of which I mount one end of a spring 47, the other end thereof being mounted at point 48, in the bracket 41. The 45 lever pawl 46, at its upper extremity has the pawl nose 49, and the point 50, carries the pin 51. This pin is operated by and works in connection with a pawl 52 which is pivotally mounted on shaft 25 and is held into 50 engagement with the ratchet 53 by the spring 54, also mounted on the shaft 25. This ratchet 53 is mounted on the main shaft 55. The pawl lever 46 engages into this ratchet 53 and operates same and the pawl 55 52 is for the purpose of holding said ratchet into its last moved position. Shaft 55 is mounted at one end in the bracket 56 and at its other end is mounted in the end plate in side 4. On the said shaft 55, I mount a 60 series of fibre discs as 57, of which there are ten, in the present instance. On the top 1, on the underneath side of same, I provide the switch contacts 58, 58.

65 Built in between two of the fibre discs 57, I place the switches contact points 59, which

turn with the discs, when the shaft 55 revolves. These switch contacts 59 are joined by wire connection 60 (see particularly Fig. 10). The circuit is formed by the knife switches 34, 34¹ entering and contacting with 70 the switch contact seats 58 and 59.

The terminals 61 and 62 lead to an electrical supply.

Connected with the terminal 62, I provide a connecting wire 63 having a terminal 64, and, at the point 65, I also connect another wire 66. Between the points 64 and 65 I provide two contact springs 67 and 68 firmly connected at one point and loose at the opposite point and capable of being pushed 80 down to make a contact.

Underneath the plate 22 I provide an auxiliary plate 69 (see Fig. 9), which is connected to the forward end of arm 28¹ and is for the purpose of allowing the user to independently throw in the switch 34¹, which 85 will be more fully described hereinafter.

In order to throw the operation of the device back to normal, I provide coiled spring 70 which has one end fastened in bracket 71 and its opposite end into shaft 55, and securely mounted on the shaft 55 I provide a stop arm 72, which when in its home or normal position, contacts with an adjusting 95 screw 73.

When the switches 34 and 34¹ are thrown into contact with their contact parts 58, 58, a circuit is formed, by reason of the knife switch contact points 70 entering the disc contacts 59, and switches 34 and 34¹ entering 100 contact points 58, 58.

In order for the above circuit to be formed, the fibre discs 57 must be in a position to receive the switches 34 and 34¹ with 105 their contacting points 59 and as the disks revolve with the shaft 44; this revolving being set in motion by the pressing of the keys, which will be hereinafter more fully described.

Under the above conditions the device 110 may operate a fan, motor, a system of lighting, or the like, which is preferably connected up for such operation, and may be used in connection with wireless or radio systems.

In order to attain the position above set forth the operator must set the same, so that such a position can be assumed and this is done through the operation of keys 8, 9, 10, 11, 12, 13, 14, 15, 16 and 17, under certain 115 system and combination between the keys and parts in connection with which they operate.

I will now give the key action and manipulation for the operation set forth in the drawings, that is one specific method of operating the device.

1st. It is necessary to push or press key 8, this will press down the lever 43, see Fig. 4, and this lever being fulcrumed in bracket 120

41 on the pin 42, will push upward on the pawl lever 49, which engages into ratchet 53, and this ratchet being fastened on main shaft 55 revolves said shaft, pawl 52 holding the revolving shaft into position; by repeating this operation the required number of times, in this present instance being three times, the shaft 55 would be revolved three steps and turn the discs 57 until the contact parts 59, 59 are in a position that the parts 70 of knife switches 34 and 34¹ will pass into engaging relation with the said contacting points 59 in the said discs.

2nd. The next step is to push down the key 10 one time, see Fig. 5, this presses downward one end of lever 31, it being fulcrumed on the shaft 25 and causes the knife switch 34 to sweep upwardly and inwardly into engagement with contacting points 59, 59, in discs 57, and 58, 58, at the upper rear portion of the device; when said lever 31 is pushed down, a pin 35 engages into the recess 36 of the lever 28, and this lever 28 being for the purpose of holding lever 31 down and the knife switch is in engagement as aforesaid.

3rd. I must now push down the key 16 and this brings the same result and condition as just described by the second step, except that the knife switch 34¹, is then brought into engagement with contact points 59 and 58, see Figs. 5 and 10.

Now all the electrical contacts and combinations have been made and set and any motor, lighting system, fan, alarm system or the like, can be put into operation and will continue in operation, until stopped by the operator. If an outsider or one not familiar with the operation of the device, pushes down any of the keys which have not been mentioned in the above operation except key 12, the circuit is broken at once by reason of plate 21 which extends entirely across under the keys and their connections, being pushed downwardly by reason of lever 28 being under the plate 21, presses same downward and releases the pin 35 on lever 31 and the spring 38 carries the knife switch out of contact and back to normal position, thus breaking the circuit.

This operation also causes an auxiliary circuit between points 67 and 68 by reason of the arm 24 pressing downwardly on the contact point 68, which is a spring, until it touches and engages the spring contact point 67, which closes the independent circuit and sends in an alarm through wire 66 and 75 by ringing a bell, flashing a light or doing any other thing for notification purposes that the device or machine has been tampered with by some other person than the one in charge thereof.

In order that the operator may stop the device from operating and break the circuit without sending in an alarm, or the like, I

provide the middle key 12 of one of the rows of keys and arrange it so that it may be pressed by said operator to stop the device, that is, break the circuit, without giving the alarm, this is done as follows:—In the upper plate 21, I provide an opening 80, see Fig. 7, which allows the stem 18 of said key 12 to pass thru and rest upon the lower plate 22, the pressure upon this key 12 will press down plate 22 independently of the keys or of said plate 21, thus breaking the circuit without giving an alarm or notice.

The keys must be worked in proper order, the keys 8, 10 and 16 are the operating keys of the present example given in this specification, and must be operated as numerically stated. In other words, supposing key 8 has been operated three times and key 16 once, if key 10 should now be pressed, key No. 16 if pressed will release by reason of the fact that the travel key 10 is greater and will consequently allow the connections made by key 16 in its function, to be released, breaking the circuit.

In the present instance, it is done as follows: If key 8 be operated three times and key 10 should not be operated next, (as it should in the operation) and key 16 is set, and the party fooling with the device should press key 10, then key 16 will be released, as pin 35 in lever 31, is in a lower position, consequently less travel to make its entry in recess 36 of the lever 28¹, than the lever 28, then if key 10 is pressed, key 16 will consequently be released.

Any other means may be employed, or combination formed in connection with the keys for breaking the circuit by the operator without sending in an alarm, other than that herein described, and just set forth.

Any particular set of keys may be used in a combination to set the device in action, which will be known only to the operator, or those interested.

While I have described one specific means and mechanism for carrying my invention into effect, it will be readily understood that the same is capable of some change and modification without departing from the principle and spirit of the invention, and I wish to be understood as claiming that any such changes and modifications will fall within the scope of this specification and claims.

What I claim as new and my invention and desire to secure by Letters Patent is:—

1. A device of the kind described including a plurality of true keys and a plurality of false keys, a movable member provided with contacts, a step-by-step mechanism controlled by one of said true keys, for actuating said member, an element for holding the movable member in the position to which it has been moved by the step-by-step

mechanism, a switch element actuated by one of the true keys and having a contact adapted to be brought into engagement with one of the contacts of the movable member, 5 a second switch element actuated by another one of the true keys and provided with a contact adapted to be brought into engagement with another one of the contacts of the movable member, stationary contacts engageable with said switch elements, latches for holding the switch elements in a position to engage the stationary contacts, and means actuated by certain of said false keys for releasing said latches.

15 2. A device as claimed in claim 1 including means actuated by another one of said false keys for releasing the element which holds the movable member in the position to which it has been moved by the step-by- 20 step mechanism.

3. A device as claimed in claim 1 in which the movable member consists of a rotatable shaft provided with a number of disks, the contacts of the movable member being arranged between certain of said disks.

4. A device as claimed in claim 1 in which the movable member is mounted on an oscillating shaft, and means for returning said shaft to a normal position.

30 5. A device as claimed in claim 1 in which the movable member is mounted on an oscil-

lating shaft, a spring for returning said shaft to a normal position, and stops for limiting the movement of the shaft under the influence of said spring.

35 6. A device as claimed in claim 1 in which each of said switch elements includes a rocking lever contacting at one end with one of the true keys and provided at its opposite end with an insulated arm carrying a switch 40 knife.

7. A device as claimed in claim 1 in which each of said latches includes a pin mounted on one of the switch elements, and a bell crank lever having a surface to engage and hold said pin.

8. A device as claimed in claim 1 in which the step-by-step mechanism includes a ratchet member fixed relatively to the movable member, a rocking lever, and a pawl connected to the rocking lever and engaging the ratchet member.

9. A device as claimed in claim 1 in which the means actuated by certain of said false keys for releasing said latches, includes superposed pivotally mounted plates engaging said latches and lying in a position to be struck by certain of said false keys.

In testimony whereof, I affix my signature at Cincinnati, Ohio, this 26 day of September, 1922.

ANTHONY A. VORNDIEKE.
